UNITED STATES PATENT OFFICE.

CHARLES JAMES BEAVER, OF HALE, ARTHUR FRANCIS WARD RICHARDS, OF BROOKLANDS, AND ERNEST ALEXANDER CLAREMONT, OF HIGH LEGH, ENGLAND.

SHEATH-COUPING FOR ELECTRIC CABLES.

1,308,390.

Specification of Letters Patent.

Patented July 1, 1919.

Application filed November 7, 1918. Serial No. 261,533.

To all whom it may concern:

Be it known that we, CHARLES JAMES BEAVER, of Hale, Cheshire, electrical engineer, ARTHUR FRANCIS WARD RICHARDS, of 5 Brooklands, Cheshire, engineer, and ERNEST ALEXANDER CLAREMONT, of High Legh, Cheshire, England, electrical engineer, subjects of the King of England, have invented certain new and useful Improvements in 10 Sheath-Couplings for Electric Cables, of which the following is a specification.

This invention relates to the bridging of a subsidiary conductor across a joint in a cable in which such conductor surrounds the 15 main conductor or conductors and is used for testing, detective and, or protective purposes and it is desired to continue such subsidiary conductor over (while still enveloping) the joint and is a modification of the 20 invention described in the specification filed on the application of us the said Charles James Beaver and Ernest Alexander Claremont No. 15821 of 1917.

This invention is useful in cases where a 25 very high pressure is not used and it is not necessary to take special precautions to prevent or minimize the stress resulting from projecting points or parts in the joint and in such cases can be used alternatively to 30 the thin metal conductor described in the said specification.

According to the present invention we 35 form a sleeve composed of metal wire conductors (preferably individually insulated and preferably with hygroscopic insulating materials) intertwined so as to form an open netting. Owing to the open netting formation the sleeve can, within limits, be elongated or shortened with a corresponding 40 contraction or expansion of its radius.

This sleeve is threaded on to one section 45 of the cable and when the joint is made is placed in position over the joint, the ends of the wires composing it being bared of insulation and tied or otherwise fastened by any convenient method to and may also be soldered to, the ends of the circular test conductor. With such a sleeve the desired 50 bridging of the joint can be readily and effectually made without interfering with access to the joint of the main conductors

for the purpose of enveloping the same with compound in the usual manner.

The accompanying drawing which illustrates an example of our invention is a sectional plan of a joint between two sections 55 of a three core cable in which a test conductor is embodied and bridged over the joint by a sleeve of metal wire entwined as above 60 described.

In said drawing *a* and *a'* designate the ends of two sections of lead covered cable having insulated cores *b*, *c*, *d*, and *b'*, *c'*, *d'* respectively and test conductors *e* and *e'*.

f designates the sleeve composed of metal 65 wire conductors each separately insulated as described and intertwined so as to form an open netting, and *g* and *g'* show ring fittings (the former being shown in section) threaded over the main insulation and to 70 which the test conductor is connected.

The bared ends of the wires comprising 75 the sleeve *f* are also connected to said rings *g*, *g'* and may be bound in position thereon by wire lappings and soldering as shown, or by any other suitable method thus establishing electrical connection between the test conductors of the two sections of cable 80 and attaining the desired end of completely surrounding the main joint.

h designates the jointing sleeve containing the completed joint and plumbed to the lead sheathing of the cable as shown at *i* and *i'*.

What we claim as our invention and desire to secure by Letters Patent of the 85 United States is:-

1. In a joint for sections of an electric cable containing a subsidiary conductor surrounding the main conductor or conductors and used for detective and/or protective purposes the combination of a sleeve composed of metal wire conductors intertwined to form an open netting threaded over the joint of the main conductor or conductors and electrically joined to the subsidiary conductors in each section of the 90 cable.

2. In a joint for sections of an electric cable in which a subsidiary conductor surrounds the main conductor or conductors, the combination of a sleeve composed of 95

metal wire conductors individually insulated preferably with hygroscopic insulating materials, said wire conductors being intertwined to form an open netting and 5 means for connecting the same to the subsidiary conductor in each section of the cable.

In witness whereof we have signed this

specification in the presence of two witnesses.

CHARLES JAMES BEAVER.

ARTHUR FRANCIS WARD RICHARDS.

ERNEST ALEXANDER CLAREMONT.
